(57) **CLAIM**

The ornamental design for an egg-shaped sculpture, as shown and described.

DESCRIPTION

FIG. 1 is a top front perspective view of an egg-shaped sculpture;

FIG. 2 is a front elevation view of the egg-shaped sculpture of FIG. 1;

FIG. 3 is a right elevation view of the egg-shaped sculpture of FIG. 1;

FIG. 4 is a rear elevation view of the egg-shaped sculpture of FIG. 1;

FIG. 5 is a left elevation view of the egg-shaped sculpture of FIG. 1;

FIG. 6 is a top elevation view of the egg-shaped sculpture of FIG. 1; and,

FIG. 7 is a bottom elevation view of the egg-shaped sculpture of FIG. 1.

The broken lines represent environmental structure and are shown for illustrative purposes only and form no part of the claimed design.

1 Claim, 7 Drawing Sheets
